ROOF DRAIN

Joseph Hirshstein, Cleveland, Ohio, assignor to
 Jesam Manufacturing Company, Cleveland,
 Ohio, a corporation of Delaware

Application November 15, 1935, Serial No. 49,999

8 Claims. (Cl. 285—37)

This invention relates to roof drains, and particularly to the means for attaching the same to a waste pipe or other drainage member.

In the ordinary construction, roof drains are generally attached to the roof structure by suitable fastening means, or the drain body may be permanently embedded in a layer of concrete, as the building specifications may require. Under the present conditions of construction, difficulty is experienced in making a joint between the outlet of the drain body and the waste pipe. The waste pipe frequently is not in alignment with the opening in the drain body and the ordinary methods of coupling are not satisfactory.

15 A further difficulty is experienced if any contraction or expansion should occur in the waste pipe line, or if there is any appreciable movement of the piping during the assemblage of the same. In both cases the utilization of the ordinary coupling means would tend to unseat the drain body when the expansion or distortion occurred, and as a consequence rupturing of connections would result.

Having in mind the difficulties experienced in roof drain constructions, it is therefore an object of my present invention to provide a roof drain construction having means for attaching the roof drain to a waste pipe which allows for the necessary expansion or contraction or misalignment 30 of the latter.

It is a further object of my invention to provide a roof drain having means for sealing and securing the waste pipe to the drain body, incorporated in the drain structure in such manner as 35 to be accessible through the top of the drain body from the roof of the building.

Further and more specific objects of my invention will appear from the following description given in connection with the accompanying drawings, where Fig. 1 is a vertical cross-section through the center of a roof drain, illustrating my invention; Fig. 2 is a fragmentary horizontal cross-section taken along the line 2—2 in Fig. 1; Fig. 3 is a vertical cross-section of a roof drain, 45 illustrating another form of my invention and Fig. 4 is a fragmentary horizontal cross-section taken along the line 4—4 in Fig. 3.

Referring now to Fig. 1, I have shown a drain body 1, embedded in a layer of concrete supported by the ordinary roof structure. Roofing material 2 is secured to the drain body by means of an annular clamping ring 3. Clamping posts 4 are carried by lugs 5 arranged at intervals around the circumference of the drain body and afford fastening means for the annular clamping ring 3.

A removable vertical dome-shaped strainer 6, and annular sediment cup 7, are seated within the recess 8 of the drain body upon a series of lugs 9. A cylindrical housing 10 is cast integrally with the drain body 1 and forms an outlet for the recess 8. The housing 10 is flanged inwardly as shown at 11, and forms a packing box adjacent the bottom opening 12, which will be hereinafter more fully described.

When the drain body 1 is set in concrete, as illustrated in Fig. 1, it becomes necessary to attach the waste pipe 20 either from the under portion of the roof or from the internal body of the drain at the surface of the roof. Experience has shown that a rigid joint between the drain body and the waste pipe is impractical. When installing the plumbing in a building, the waste pipes 20 will vary in their lengths considerably, and thus, in one instance, a longer coupling between the waste pipe and the outlet to the drain 20 will be required than in another. Misalignment of the pipe line or any undue expansion or contraction will necessarily prohibit the use of a rigid connection between the bottom portion of the drain and the waste pipe.

To obviate these difficulties and to facilitate the connection of waste pipes to drain bodies under various conditions of construction, I have provided an expansible and contractible connector which is capable of being inserted from the under portion of the roof and which may be sealed and connected to the drain body from the internal recess therein on the upper surface of the roof.

The waste pipe 20 may be cut off to any convenient length below the outlet of the drain body. A thin walled cylindrical sleeve 21 is then secured to the waste pipe 20 by means of a threaded connector 22. The length of this tubing will be dependent upon the variable distance between the top of the waste pipe and the lower opening in the drain body to be connected.

Having cut the sleeve 21 to the proper length, it may either be inserted in the opening 12 and then secured by the connector 22, or the sleeve 45 may be first attached to the waste pipe 20 and the entire arrangement inserted into the opening 12. The drain body opening 12 may be considerably larger than the outer diameter of the sleeve 21 to allow for any misalignment of the drain and plumbing assembly. It may thus be seen that no accurate alignment of the waste pipe 20 is necessary, so long as a sufficient length of the sleeve 21 is inserted in the opening 12. It is further apparent that the distance between the 55

waste pipe 20 and the opening 12 does not require the accurate positioning which would be necessary if a coupling or other screw-type joint were to be employed.

5 Having extended a sufficient portion of the sleeve 21 in the bottom of the drain body, the operation of tightening the same may be done entirely from the surface of the roof. In building constructions this element is important, as 10 the workers below may slip the sleeves 21 into the drain while an assistant on the roof may, at the same time, or any period later, apply the clamping means. Where the time element is important, this construction facilitates present building 15 methods.

With the strainer 6 and sediment cup 7 removed, the workman may then proceed to apply the seal between the sleeve 21 and the housing 10. An asbestos packing gland 23 or other suitable material is wound around the sleeve 21 within the recess formed by the flange 11. An annular gland ring 24 is then inserted between the opening formed by the sleeve 21 and the housing 10. It may thus be seen that by a downward 25 pressure of the gland ring 24, the gland material 23 will be compressed against the outer wall of the sleeve 21 so that a seal is formed between the waste pipe 20 and the lower housing of the drain body 10.

30 A series of slots 30 are disposed at spaced intervals around the circumference of the opening 28 in the bottom of the recess 8. Each slot has an opening 31 in its upper wall and at its one end thereof, so that a lug may be inserted there- 35 in.

An annular pressure ring 25, carrying threaded bolts 26, is then inserted within the opening 28 at the bottom of the drain body. On the outer periphery of the ring 25 are disposed a series of 40 lugs corresponding in number and position to the openings 31 in the slots 30. The ring 25, being thus inserted in the opening 28 and turned in a clockwise direction, will be locked against any upward movement by reason of the upper 45 shoulder of the slot 30. In this position the bolts 26 will rest upon the upper surface of the gland ring 24. The tightening of the bolts 26 will then apply pressure to the gland ring 24 and compress the gland 23 so that a seal is formed between the 50 outer surface of the sleeve 21 and the inner surface of the flange 11.

The construction heretofore described has merit in present building methods in that it allows for the insertion of the waste pipe from the 55 underside of the roof, while all of the connections and replacements may be made from the surface of the roof. The necessity of accurate alignment between the waste pipe 20 and the bottom opening of the drain 12 is thereby obviated, while in 60 addition any expansion or contraction within the pipe line will be compensated when that condition prevails. Inspection of the drains and expansion joint parts may be made as conveniently after the completion of the building 65 as before.

In Fig. 3 I have shown another form of my invention embodying the construction illustrated in Fig. 1. It has been found that the packing material around the waste pipe connection may 70 become worn and that seepage may result between the drain body and the sleeve 21. To eliminate this, I have provided an arrangement whereby the seal is made internally of the sleeve 21, rather than externally, as illustrated in Fig. 75 1 of my drawings.

Referring now to Fig. 3, I have shown a drain body construction similar to that illustrated in Fig. 1. The cylindrical housing 10, disposed at the bottom of the drain body, now acts as a skirt for the sleeve 21. As in the construction shown in Fig. 1, the drain body opening is made preferably larger than the outer diameter of the sleeve 21 for the purpose hereinbefore stated. A stationary annular gland ring 40 is cast integrally with the drain body and forms an annular recess 5 between the cylindrical housing 10 and the gland ring 40. A stationary pressure ring 41, provided with threaded bolts 42, is disposed at the bottom opening 28 of the recess 8 in the drain body. The movable gland ring 43 is supported by its 10 threaded engagement with the bolts 42, so that the tightening of the same will impart to the gland an upward pressure.

The assembly of parts is made in the same manner as that described in Fig. 1. The movable gland ring 43 is loosely carried by the bolts 42. The sleeve 21 connected to the waste pipe 20, may then be inserted between the cylindrical housing 10 and the stationary gland ring 40, the later sleeve having just been cut to the proper length, so that the necessary expansion may be accommodated.

With the dome-shaped strainer 6 and the sediment cup 7 removed, the operation of applying the seal can be accomplished from the roof of the building. By loosening the bolts 42 the movable gland ring 43 will drop into the sleeve 21, until the connector 22 is reached. The connector 22 should be of sufficient length to allow ample space for the insertion of the gland material 23. This is accomplished by merely winding the same around the removable gland ring 43, and between the inner surface of the sleeve 21.

Upon the completion of this operation the hand may then be inserted within the ring 43 to position the same and reengage the bolts 42. The tightening of the bolts will thereby compress the packing material 23 between the stationary and movable glands and against the inner wall of the sleeve 21. In the event that any water should become lodged between the movable gland ring 43 and the stationary ring 40, I have provided small seepage holes 45 so that the recess between the rings may be properly 50 drained.

It may therefore be seen that I have invented a new and useful joint for connecting waste pipes to roof drains, so that the waste pipe may be inserted from the interior of the building, and that all connections and repairs may be made from the roof of the building. I have further provided a joint which will compensate for any expansion, contraction or misalignment of the draining members, and one that may be 55 60 65 70 75 80 85 90 95 100 105 110 115 120 125 130 ing therein, a waste pipe slidably inserted within said housing, a packing gland and a packing ring slidably mounted between said waste pipe and said housing, a removable pressure ring disposed within the bottom opening in said drain body, a series of grooves arranged within said opening, a complementary series of lugs carried by the pressure ring to engage said grooves, and clamping means carried by the pressure ring for applying a pressure to the packing ring.

3. In a roof drain, a drain body having an opening in the bottom thereof, a housing disposed around said opening, a sleeve secured to a waste pipe slidably inserted within said housing, and operative means disposed internally of said drain body for sealing and securing said housing to the internal surface of the sleeve, said means being accessible and adjustable from the surface of the roof after the drain body has been secured 20 and sealed thereto.

4. In a roof drain, a drain body having an opening in the bottom thereof, a housing disposed around said opening, a waste pipe slidably inserted within said housing, a packing gland and a packing ring slidably disposed within said waste pipe, and fastening means secured to the opening in the bottom of said drain body for applying a pressure to the packing ring to compress the gland, said means being accessible and adjustable internally of the drain body, after the drain body has been secured and sealed to the roof.

5. A roof drain comprising a drain body having an opening in the bottom thereof, a housing extending downwardly from said opening, a packing gland and a packing ring disposed within the housing, a recess between said housing and the packing ring, a waste pipe slidably inserted within said recess, a stationary pressure ring disposed within the opening in said drain body and means carried by said pressure ring for applying pressure to said packing ring, said means being

adjustable from the surface of the roof after the drain body has been secured and sealed thereto.

6. A roof drain comprising a drain body, having a housing disposed around the bottom opening therein, a stationary gland ring carried by said drain body internally of the housing, a movable packing ring slidably mounted within said stationary ring, a waste pipe slidably inserted between said housing and said packing ring, a packing gland disposed between the packing ring and the internal surface of the waste pipe, and clamping means carried by the opening in said drain body to compress the movable packing ring against the stationary ring and seal the drain body to the waste pipe, said clamping means being adjustable from the surface of the roof after the drain body has been secured and sealed thereto.

7. An expansible roof connection, comprising a body portion having an enlarged recess therein, a waste pipe extending into said recess, a packing ring and a packing gland slidably mounted within said recess, a pressure ring secured to the body portion and removable relative thereto, and adjustable means reacting against the pressure ring 20 for applying pressure to the packing ring.

8. An expansible roof connection, comprising a body member having a flanged portion adapted to be secured to the roof, an enlarged recess in said body member and a waste pipe extending 30 therein, a packing gland and a packing ring slidably mounted within the recess, a pressure ring carried by the body portion having adjustable means reacting thereon for applying pressure to the packing ring, and a clamping ring co-acting with the flanged portion for sealing and securing the body member to the roof, said packing members being accessible for adjustment or replacement independently of the clamping ring 35 for sealing the body member to the roof.

JOSEPH HIRSHSTEIN.
